FILLING MACHINE

John P. Jakob, Roselle, N. J., assignor to American Can Company, New York, N. Y., a corporation of New Jersey

Application December 17, 1947, Serial No. 792,273

10 Claims. (Cl. 226—14)

1

This invention relates to machines for assembling articles such as cans for filling into bags or other containers and has particular reference to assembling cans in layers and rows and forming a stack of improved structure for filling as a unit into the bag.

An object of the invention is the provision of a machine for receiving rows of cans in one plane as a layer and for forming the layer into stacks by shifting out of the plane each layer of cans as formed and for filling the unit stack into a bag.

Another object of the invention is the provision of a machine of the character described for receiving separated rows of cans in one plane as a layer and for forming the layers into stacks by shifting out of the plane each layer of cans as formed, for bringing a divider sheet into the space between adjacent rows and for bringing the rows into closer position to form a unit stack and for filling the unit stack into a bag.

Another object of the invention is the provision of such a machine for receiving rows of cans and for arranging them in superimposed layers or tiers forming a unit stack and for filling the assembled cans as a group into a bag, wherein the individual rows of cans in each layer are offset or staggered relative to the adjacent rows and layers to interlock the assemblage of cans.

Numerous other objects and advantages of the invention will be apparent as it is better understood from the following description, which, taken in connection with the accompanying drawings, discloses a preferred embodiment thereof.

Referring to the drawings:

Figure 1 is a side elevational view of a machine for assembling, stacking and filling cans into bags;

Fig. 2 is a top plan view of the machine shown in Fig. 1;

Fig. 3 is a view similar to Fig. 2 with parts broken away and parts shown in section;

Fig. 4 is a perspective view showing a unit stack of cans arranged for filling into bags or flexible containers;

Fig. 5 is a front elevational view of the machine shown in Fig. 1 with parts broken away and parts shown in section;

Fig. 6 is a perspective view showing spaced assembly tracks for receiving rows of cans and means for shifting the tracks; and

Figs. 7 and 8 are enlarged details showing a can supported on the tracks and in the process of being lowered therebetween.

As an exemplary embodiment of the invention the drawings illustrate a machine into which empty or filled cans A are fed in spaced, parallel rows preferably in one plane to form a layer or

tier having a predetermined number of cans in each layer. After being assembled the individual layers are moved or lowered into other planes to arrange the layers into superimposed relation and to form a unit stack. Such a stack of cans then is shifted to bring all the cans in the unit into a compact arrangement, with a divider sheet placed between the rows and the unit stack thereafter pushed through a single stroke to shift it and to deposit it into an opened bag or flexible container.

Cans A are fed to the instant machine in any suitable manner leading to an inclined runway 21 secured to the top of a frame 22 mounted on a base 23, which, with the frame comprises the main frame of the machine (Figs. 1 and 2). Runway 21 includes a plurality of spaced angle irons 24, arranged in parallel relation and in a manner to support and guide the cans, so that four rows of cans may be fed or rolled downwardly by gravity simultaneously.

The cans A are retained in the runway 21 by gates 25 located at the terminal or lower inner end of the runway (Figs. 1, 2 and 5). Gates 25 are mounted on a rock shaft 26 carried in suitable bearings in brackets 27 secured to the frame 22. Shaft 26 is actuated by a rock lever 28 which is secured to this shaft. Lever 28 is cam actuated by a cam operating lever 31, the outer ends of these levers being connected through a link 32 (Fig. 1).

The cam operating lever 31 is carried on a shaft 33 mounted in a bracket 34 which is secured to the frame 22 (Figs. 1 and 3). The lever 31 carries a cam roller 35 which operates in a cam raceway 36 of a barrel cam 37 mounted on a vertical shaft 38 journaled in upper and lower bearings 41, 42 secured to the main frame 22 and the base 23 of the machine.

Shaft 38 carries and is rotated by a helical gear 43 which meshes with and is driven by a helical gear 44 mounted on a horizontal shaft 45 journaled in bearings 46, 47 secured to the frame 22 (Fig. 3). Shaft 45 carries and is rotated by a worm wheel 48 which meshes with and is driven by a worm 51 secured to a drive shaft 52 journaled in a bearing 53 secured to the frame 22. Shaft 52 constitutes the main drive shaft of the machine and may be driven in any suitable manner.

The gates 25 are lifted at intervals to permit a predetermined number of cans from the runways 21 to roll forward between a plurality of spaced and parallel vertically disposed guide plates 54 which at their ends are secured to the main frame 22 in any suitable manner. A stop bar 55 carried in the outer ends of the plates 54 arrests the travel of the cans and locates them in a predetermined position.

The cans A as they roll forward, travel along

and are supported on a plurality of spaced assembly tracks 56, 57 (Figs. 1, 2 and 6) located adjacent the guide plates 54. These tracks are in effect continuations of the runway tracks 24, and are formed from horizontally disposed angle irons. It is upon these tracks that successive layers or tiers of the cans are assembled preparatory to being lowered in superimposed relation for forming a unit stack.

The assembly tracks 56, 57 are mounted on 10 spacer blocks 58 (Fig. 6) and are secured at their ends to transverse shift rails 61, 62, 63, 64 in a suitable manner so that the tracks 56 and the tracks 57 may be spread apart when required. The forward ends of the tracks 56 (as viewed in Fig. 6) are secured to the transverse shift rail 61 and the rear ends of these tracks are secured to the transverse shift rail 62. In similar manner, the forward ends of the tracks 57 are secured to the transverse shift rail 63 and the rear ends of these tracks are secured to the transverse shift rail 64.

The transverse shift rails 61, 62, 63 and 64 are pivotally connected to the lower ends of depending rock levers mounted on rock shafts 65, 66 carried in bearings 67, 68 in the top of the frame 22 (Figs. 1, 2, and 5). Shift rails 61, 62 are connected at one end to levers 71, 72 secured to rock shaft 65 and at the other end to levers 73, 74 carried on the rock shaft 66. Similarly, shift rails 63, 64 are connected at one end to levers 75, 76 carried on the rock shaft 65 and at the other end to levers 77, 78 secured to rock shaft 66.

The rock shafts 65, 66 (Fig. 6) are cam actuated by means of levers 81, 82 secured to these shafts. Links 83, 84 connect the lower ends of levers 81, 82 to the upper and lower arms of a cam operating lever 85 which is carried on a shaft 86 secured in the frame 22 (Figs. 1, 3, 5 and 6). The lever 85 is formed with a lower extension having a pin 87 carrying a cam roller 88 which operates within a cam raceway 91 of a barrel cam 92 mounted on the horizontal shaft 45.

Cam 92 controls the movement of the assembly tracks 56, 57 and is operated in time with the cam 37 so that when the gates 25 are lifted, the tracks 56, 57 will be in a normal or closed position (Figs. 6 and 7) for receiving rows of cans for assembling them into a layer.

As an incident to forming a unit stack of cans, a sheet or divider B preferably formed of fibrous material is inserted into spaces 94 between cooperating sets of tracks 56, 57 to separate the rows of cans vertically as they are arranged in superimposed rows. If desired such a sheet may also be inserted at the left of the first row of cans A (as viewed in Figs. 2 and 5) for providing an end member or wall at the opened end of the bag into which the cans are filled.

Sheet or divider guides 95 are provided for supporting the sheets B in vertical position and these are secured to the top of the frame 22. The divider guides are formed of sheet metal having spaced walls between which the sheets B are retained so that they may be lowered step by step with each layer of cans as successive layers of cans are added for forming the unit stack.

Sheets B may be placed into the divider guides 95 manually, prior to or just following the assembly of the initial layer of cans upon the tracks 56, 57 for forming a unit stack (Figs. 1, 2 and 5). The lower edges of the sheets B rest upon a movable platform 97 which at this time is raised to

its uppermost position beneath the assembly tracks.

The platform 97 is rectangular in outline and is mounted on the upper end of a vertical stem or shaft 98 which is telescopically carried within a sleeve 101, slideable in a pedestal 102 secured to the base 23. The platform 97 is raised and lowered by a lifter lever 103 loosely mounted on a pivot shaft 104 secured in the frame 22 (Figs. 1, 3 and 5). The lever intermediate its ends carries a cam roller 105 which operates within a cam raceway 106 of a barrel cam 107 mounted on the shaft 38. The inner end of lever 103 engages the platform shaft 98 in a ball and socket joint 108 for effecting the movement of the platform 97 in time with other operations of the machine.

The sleeve 101 and the pedestal 102 are provided with respective clearance slots 111, 112 for movement of the lever 103. These slots 111, 112 are kept in alignment by a tongue 113 which is formed on the lower end of the sleeve 101 and which is located and slideable in the slot 112.

The platform 97 is movable in an assembly frame or enclosure 114 (Figs. 1, 3 and 5) within which the layers of assembled cans are arranged. The assembly frame is formed by side plates 115, 116 secured to the main frame 22 (Fig. 1). It is against these walls that the cans A engage as the platform 97 is lowered with superimposed layers of cans. The frame 114 is open at both ends to facilitate the removal of unit stacks from the machine.

With the platform 97 raised and the divider sheets B in place as illustrated in Fig. 1, the initial layer of assembled cans A on the assembly tracks now are lowered onto the platform 97. This is effected by spreading apart or opening the tracks 56, 57 from their normally closed position for dropping the rows of cans therebetween (Fig. 8). The platform 97 meanwhile stands still to receive the cans and the gates 25 remain in their lowered position holding back the supply of cans in the runways.

As the initial layer of cans is deposited on the platform the adjacent rows of cans are crowded to opposite ends of the rows or sides of the assembly frame in order to arrange the cans in staggered relation. This is done by retractable elements 117 pivotally carried on pins 118 in brackets 121 secured to the bottom face of the platform 97 in an offset relation (Figs. 1 and 3).

The retractable elements 117 are formed to provide bent prongs or fingers 122 at one end and an extended arm which is weighted at 123 at the opposite end. Fingers 122 extend upwardly through openings 124 in the platform and engage the cans at opposite ends of adjacent rows and thus holds these rows in place on the platform in a staggered relation.

The platform after receiving its initial layer of assembled cans is moved down to a plane, a distance substantially equal to the diameter of the can A preparatory to receiving a second layer. The divider sheets B disposed between the ends 65 of the cans move down with the platform. The assembly tracks 56, 57 meanwhile have moved together again into their closed position for receiving an additional supply of cans from the runways for assembling them into a second layer.

The operations of opening the assembly tracks 56, 57 thereafter are repeated and the second layer of cans are dropped down, this time onto the initial layer already disposed in staggered relation on the platform. The cans of this second layer, guided by the side plates 115, 116 of

the frame 114, fall into position on the curved surfaces between adjacent cans of the initial layer and thus stagger the cans relative to the initial layer.

The operations of the gates 25 and the assembly tracks 56, 57 are continued as hereinbefore described in time with the lowering of the platform 97 successively, in step-by-step relation until the platform is fully loaded with superimposed layers of cans. The platform at such a time reaches a position at the bottom of the assembly frame 114 where it dwells momentarily while the stack of cans as a unit is discharged therefrom. Just before the platform reaches the bottom of the assembly frame, the fingers 122 of the retractable elements release their hold on the cans in the initial layer and are withdrawn from the openings 124. This is effected by the weighted ends 123 of the arms engaging against a stationary horizontal plate 126 secured to the frame 22.

The superimposed layers of cans are now free to be shifted endwise to bring all the cans in the adjacent rows together into a compact assembly and to thereafter continue the shifting thereof (to the right as viewed in Figs. 2 and 5) into an opened bag C disposed in position at an opened end of the assembly frame 114. Fig. 4 of the drawings illustrates a unit stack D of cans after being pushed together with the dividers B positioned between the rows. The rows of cans are disposed in a novel staggered relation laterally, longitudinally and vertically and are thus interlocked in such a manner as to provide a firm compact stack ready for insertion as a unit in the opened bag C.

The bag C comprises a flexible container, shipping carrier or the like formed of flexible material such as paper and when in an expanded condition forms a square or rectangular container having four side walls and a bottom. Such a container or bag is shown held in opened position on mandrel units 127 and corner rods 128 secured to the machine frame (Figs. 2, 3 and 5). The big C is placed in position by hand.

Provision is made for shifting the stack D of cans as a unit, into the bag C, in a single stroke. This is done by means of a stack shifting device 131 mounted on a frame extension 132 of the machine frame (Figs. 2 and 5). Such a device operates a movable wall or pusher plate 133 which is carried at one end of the device and which is movable into and through the assembly frame 114 for effecting the shifting of the unit stack from the platform 97 into the bag C.

A device 131 (Fig. 5) includes an air cylinder 134 having a cylinder head 135 secured to one end and a telescopic sliding unit 136 operable within the cylinder. Such a unit includes a piston 137 and an auxiliary or inner piston 138. Piston 137 is formed on the inner end of the unit 136 and is slidable within the cylinder 134. Auxiliary piston 138 is formed on the inner end of a piston rod 141 slidable within an auxiliary cylinder 142 of the unit 136. Piston rod 141 is slidable in a bore 143 of the unit 136 and has its outer end secured to the movable plate 133.

Control of the stack shifting device 131 is effected through a valve 145 which is connected thereto by suitable pipe connections (Fig. 5). Valve 145 comprises a housing 146 having a bore 147 within which a stem or plunger 148 is slidable. The housing 146 is provided with an inlet connection 151 which communicates with the bore 147

for supplying compressed air from any suitable source to this valve.

The opposite side of the housing 146 is provided with pipe fittings 152, 153 which communicate with the bore 147. Pipe connection 154 connects the fitting 152 with an inlet opening 155 in the cylinder head 135. Pipe connection 156 connects the fittings 153 with a telescopic pipe connection 157 secured to the cylinder 134. An inner pipe 158 is slidable in the telescopic pipe connection 157 and leads to an inlet opening 161 in the unit 136 wherein it is secured. A pipe connection 162 connects the fitting 153 with an inlet opening 163 in the cylinder 134.

The stem 148 (Fig. 5) is formed with a reduced section 164 intermediate its ends for providing an air passage 165 surrounding it within the bore 147 so that the inlet pipe connection 151 may have communication with openings in the pipe fittings 152, 153 as the stem is moved within the bore 147. Stem 148 also is formed with outlet openings 166, 167 which have communication with openings in the pipe fittings and also with the outside atmosphere when the stem 148 moves into different positions.

The valve 145 is actuated by a solenoid 171 in proper time with other operations of the machine for controlling the movement of the stem 148 and thus effecting the operation of the stack shifting device 131. The stem 148 normally is held in an inoperative position by a spring 172 which is retained in place by a wall extension 173 secured to the housing 146.

The solenoid 171 is energized through a normally open switch 174 which is mounted on the frame 22. Provision is made to operate this switch by a cam segment 175 on the cam 107 which closes the switch at the desired time (Fig. 1).

The switch 174 is connected by a wire 176 to a source of electric current, such as a generator 177 (Fig. 5) which in turn is connected by a wire 178 to one side of the solenoid 171. A wire 181 connects the other side of the solenoid with the switch.

Hence, as the solenoid is energized through closing of the switch 174, the stem 148 is shifted within the bore 147 and closes the air supply to the opening in the pipe fitting 153 and brings the outlet opening 167 into communication with it for bleeding air in the device 131 to the atmosphere. This action also uncovers the opening in the pipe fitting 152 to a supply of air from the pipe connection 151. A supply of compressed air then passes through the valve 145, pipe fitting 152, pipe connection 154, inlet opening 155 into the air cylinder 134 thus forcing both the pistons 137, 138 to move toward the right (Fig. 5).

Piston 137 reaches the end of its stroke when it engages against a wall 185 of the air cylinder 134 whereupon the piston 138 continues to move within the unit 136 until it reaches the end of its stroke engaging against a wall 186 at the end of the unit. During this stroke of the shifting device 131 the unit stack of cans is shifted by the plate 133 and deposited into the bag C at the opposite side of the machine.

At the end of this shifting stroke of the shifting device 131, the switch 174 is opened and the solenoid 171 is deenergized. The spring 172 thereupon moves the stem 148 to the right as viewed in Fig. 5 and closes off the supply of air to the fitting 152 and uncovers it to the outlet opening 166 for bleeding the air in the device 131 to the outside atmosphere. This action also

uncovers the opening in the pipe fitting 153 to a supply of compressed air and allows it to pass into pipe connections 156, 162, telescopic pipe connections 157, 158 and inlet openings 161, 163 into the outer and inner cylinders 134, 142 for moving the pistons 137, 138 toward the left (as viewed in Fig. 5). Hence, the parts of the device 131 and the movable plate 133 are returned to their normal position (Fig. 5) where they remain until the next unit stack of cans is ready for shifting as hereinbefore explained.

The operations of the machine thereafter are repeated as the platform 97 moves upwardly again to receive a subsequent or initial layer of cans which are fed in, assembled and discharged upon the platform as previously described.

The filled bag C meanwhile is withdrawn manually or in any other suitable manner, from the mandrel units 127 and the corner rods 128 for discharge from the machine, whereupon another bag C is slipped in position on the units and the rods for receiving the next unit stack of cans.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for assembling articles such as cans or the like into stacked formation for filling into bags or other containers, the combination of a can assembling frame for receiving individual layers of rows of cans, a movable platform within said frame for supporting the cans, pivot elements carried on said platform for engaging the adjacent rows of an initial layer of cans for locating them in staggered relation, means for moving said platform to receive successive layers of cans, and means for pushing the assembled cans as a unitary stack from said frame into an opened bag.

2. In a machine for assembling articles such as cans or the like into stacked formation for filling into bags or other containers, the combination of spaced tracks for receiving rows of cans and for supporting the cans to form a layer, a can assembling frame located adjacent said tracks, means for moving the tracks in each row to withdraw the support from the cans thus releasing each layer of cans for discharge into said frame, and means for pushing the assembled rows and layers of cans from said frame into an opened bag.

3. In a machine for assembling articles such as cans or the like into stacked formation for filling into bags or other containers, the combination of a plurality of spaced tracks disposed in a horizontal plane for receiving cans and for supporting the cans in parallel rows to form a layer, a can assembling frame located beneath said tracks, means for separating adjacent track sections in each row of cans for removing the can support and for releasing successive layers of cans to allow each layer to drop into said frame, a movable platform within said frame for supporting the layers of cans, and means for pushing the assembled cans from said frame into an opened bag.

4. In a machine for assembling articles such as cans or the like into stacked formation for

filling into bags and other containers, the combination of a plurality of tracks for receiving rows of cans, said tracks being divided into a pair of spaced track sections for supporting each row of cans with all track sections parallel to form a layer, a can assembling frame located beneath said tracks, a movable platform within said frame for supporting the cans, means for moving each pair of track sections to withdraw the can support for depositing successive layers of cans into said frame, means for staggering the cans in a layer as they are deposited upon said platform, and means for pushing the assembled and staggered cans from said frame into an opened bag.

5. In a machine for assembling articles such as cans or the like into stacked formation for filling into bags and other containers, the combination of a can assembling frame for receiving individual layers of separated rows of cans, a plurality of spaced tracks for supporting cans in parallel rows to form a layer, a movable platform within said frame for supporting the cans, means for moving said platform to receive successive layers of cans, guide means located above the spaces between said tracks for guiding a divider sheet between adjacent rows of cans on said tracks, the divider sheet resting on and moving with said platform, and means for pushing the separated rows of cans together with a said divider sheet between adjacent rows preparatory to filling the assembled cans into an opened bag.

6. In a machine for assembling articles such as cylindrical cans and the like into stacked formation for filling into bags or other containers, the combination of a plurality of spaced inclined tracks for receiving rolling cans and for supporting a predetermined number of cans in each row to form a layer, a can assembling frame located beneath said tracks, means for separating spaced tracks in the rows for withdrawing can support thus releasing a layer of cans for deposit into said frame, and means for pushing the assembled layers of cans endwise from said frame into an opened bag.

7. In a machine for assembling articles such as cans or the like into stacked formation for filling into bags or other containers, the combination of a can assembling frame for receiving individual layers of rows of cans, a movable platform within said frame for supporting the cans, retractable elements carried on said platform for engaging the adjacent rows of an initial layer of cans for locating and for holding them in staggered relation, means for moving said platform to receive successive layers of cans, means engageable with said elements for moving them out of engagement with said staggered cans are deposited upon said platform, and means for pushing the assembled cans from said frame into an opened bag.

8. In a machine for assembling articles such as cans or the like into stacked formation for filling into bags or other containers, the combination of a can runway for the advancement of spaced rows of cans, spaced tracks located at the terminal end of said runway for receiving rows of cans from the runway to form a layer of cans, movable gates at the junction of said runway and said tracks for retaining cans in said runway after releasing a predetermined number of cans in each row of said layer of cans on said spaced tracks, a can assembling frame located beneath said tracks, means for moving

said tracks to withdraw support from the cans thereby depositing successive layers of cans into said frame, said track moving means restoring said tracks in container supporting position after deposit on each layer of cans, means for moving said gates to supply said emptied tracks with cans, a movable platform within said frame for supporting the cans, means for lowering said platform for individual layers of cans, and means for pushing the assembled cans from said frame into an opened bag.

9. In a machine for assembling articles such as cans or the like into stacked formation for filling into bags or other containers, the combination of a can assembling frame for receiving individual layers of rows of cans, a movable platform within said frame for supporting the cans, movable means carried on said platform for locating the cans in staggered relation, said staggering means engaging alternate rows of cans at different ends of the row, means for moving said platform with its staggered can rows to receive successive layers of cans on top of the preceding layer, means secured to said assembling frame and projecting laterally therefrom for supporting a bag to be filled, and means for pushing the assembled cans laterally as a unitary stack from said frame into said held bag.

10. In a machine for assembling articles such as cans or the like into stacked formation for

filling into bags or other containers, the combination of a can assembling frame having a pair of vertically disposed side walls for receiving individual layers of rows of cans, means for delivering a predetermined number of cans in individual rows to said assembling frame, a platform movable between said side walls within said frame for supporting the cans, means carried on said platform adjacent said side walls and engageable at alternate ends of adjacent rows of the initial layer of cans on said platform for shifting the cans in each row against an opposite side wall to locate alternate rows in staggered relation, means for lowering said platform to receive each successive layer of cans on the preceding layer in staggered relation, and means for pushing the assembled staggered cans as a unitary stack from said frame into an opened bag.
